UNITED STATES PATENT OFFICE

AUGUST S. LISS, OF CHICAGO, ILLINOIS, ASSIGNOR TO WESTERN ELECTRIC COMPANY,
INCORPORATED, OF NEW YORK, N. Y., A CORPORATION OF NEW YORK

MATERIAL FEEDING APPARATUS

Application filed February 15, 1930. Serial No. 428,662.

This invention relates to a material feeding apparatus, and more particularly to an apparatus for automatically feeding articles of manufacture to material processing machines.

The principal object of this invention is to provide a material feeding apparatus which is adaptable to various types of processing machines and which will more efficiently expedite production.

In accordance with the general features of the invention, there is provided a material feeding apparatus employing a piston reciprocating in a cylinder in response to the opening and closing of air ports extending thereto upon the operation of two slide valves which are actuated independently in accordance with the operation of pivotally mounted cams on the punch holder of the reciprocating part of a punch press. One of these cams is arranged to be effective for operating its associated slide valve upon the downstroke of the head of the press and ineffective on its upstroke, while the other cam is ineffective on its downstroke and effective upon its upstroke, thereby properly controlling the inlet and exhaust ports to the cylinder to cause the piston to travel in the proper direction. The piston, through suitable plungers, operates a yoke which moves a plate past an opening in a magazine, picks a part therefrom and advances the part along a channel extending to the die of the punch press and repeating this operation during the reciprocal movement thereof so as to feed successively the parts to the channel and move the parts to the die.

Other objects and advantages of the invention will become apparent from the following detailed description of one embodiment thereof, reference being had to the accompanying drawings, wherein

Fig. 1 is a top plan view of the apparatus with the reciprocating punch holder and the punch removed;

Fig. 2 is a sectional view taken along the line 2—2 of Fig. 1;

Fig. 3 is a front elevational view of the apparatus;

Fig. 4 is a sectional view taken along the line 4—4 of Fig. 1;

Fig. 5 is a plan sectional view taken along the line 5—5 of Fig. 2;

Fig. 6 is a sectional view taken along the line 6—6 of Fig. 1;

Fig. 7 is a longitudinal vertical sectional view taken along the line 7—7 of Fig. 1, and

Figs. 8 and 9 are detail views of the article of manufacture shown respectively before and after a forming operation.

Referring now to the drawings in which like reference numerals designate similar parts throughout the several views, the numeral 11 designates a suitable base at the forward end of which is mounted a die block 12 having suitable apertures 13 and 14 therein for receiving die plates 15 and 16 respectively. The die plates 15 and 16 are rigidly held in the die block 12 by any suitable means such as machine screws 17 and have disposed therebetween a die plunger or knockout 18 which is normally held in its uppermost position by a spring 19.

Upon the base 11 and at the rear of the die block 12 is disposed a housing 21 having a cover 22 upon which is mounted a magazine 23 for receiving the parts or articles of manufacture to be formed. The magazine 23 has disposed its lower end in communication with an aperture 24 of the cover 22 through which a feed block or member 25 extends. The feed block 25 is rigidly mounted upon a reciprocating member or yoke 26 and has a reduced portion 27 which provides an abutting shoulder 28 for a purpose hereinafter described.

Disposed between jaw portions 29 of the yoke 26 is a piston 31, which is movably disposed in a cylinder 32, and which has piston rods or stems 33 extending outwardly in general alignment with each other and in axial alignment with the piston 31 through apertures in cylinder heads 34—34 to abutting engagement with the jaw portions 29. The cylinder 32 as well as a valve casing 35 are secured to and carried by the base 11. The piston 31 is actuated by any desired fluid such as air under pressure entering the cylinder 32. The air under pressure is controlled by slide valves 36 and 37 which are respectively disposed in apertures 38 and 39 of the valve casing 35. Annular grooves 41 and 42 are

disposed at spaced apart positions concentric with the slide valve 36 and are adapted to be moved into communication with spaced apart air ports 43 and 44 which communicate with the ends of the cylinder 32 through the cylinder heads 34. These annular grooves are normally held out of communication with the air ports 43 and 44 by a spring 45 which is disposed concentric with the valve 36, and has one end disposed in abutting relation with a collar 46 which is pinned to the valve. The valve 37 is also provided with annular grooves 47 and 48 which are adapted to be moved into communication with the air ports 43 and 44 respectively, but which are held out of communication with these air ports by means of a spring 49, the latter being disposed concentric with the valve 37 and having one end in abutting relation with a collar 51 which is disposed concentric with the valve and pinned thereto.

The slide valves 36 and 37 are alternately actuated by cam levers 52 and 53 respectively, which are adjustably mounted upon a reciprocating punch holder 54 by adjustable pivot blocks 55 and 56 respectively, in which the actuating cam levers are pivotally mounted. The adjustable pivot blocks 55 and 56 (Fig. 6) are provided with elongated openings 57 and 58 therein, through which a securing means such as machine screws 59 extend for adjustably securing the pivot blocks in place upon the rear portion of the punch holder 54 (Fig. 7). The cam levers 52 and 53 are normally held inwardly by means of springs 61 which are carried by the pivot blocks 55 and 56. Stop members 62 in the form of integral lugs are disposed adjacent the pivot ends of the cam levers 52 and 53 for limiting the inward movement of the cam levers. The lower end of the cam lever 52 is provided with an actuating cam surface 63 (Fig. 4) which is arranged to engage with an actuating cam surface 64 of the slide valve 36. The cam lever 52 is also provided with a cam surface 65 which is arranged to engage a cam surface 66 of the slide valve 36 for allowing the cam lever 52 to be moved upwardly without actuating the valve 36. The cam lever 53 is provided with a cam surface 67 (Fig. 6) which is arranged to engage with a cam surface 68 of the slide valve 37 for allowing the cam lever 53 to be moved downwardly without actuating the valve 37. The cam lever 53 is, however, provided with an actuating cam surface 69 (Fig. 5) which is arranged to engage with an actuating cam surface 71 of the lever 37 or actuating the lever 37 when the cam lever 53 is moved upwardly.

From the foregoing description in the various parts of the apparatus, the operation thereof will be more clearly understood. In the present embodiment a plurality of parts 65 or articles of manufacture, as indicated at

72, are disposed in the vertically extending magazine 23 so that the lowermost part will rest upon the feed block 25. Upon downward movement of the punch holder 54 the slide valve 36 will be moved to the left (Fig. 7) by the movement of the actuating cam surface 63 of the cam lever 52 over the actuating cam surface 64 of the valve 36. This inward movement of the slide valve 36 will position the annular groove 41 in communication with the air port 43 thus allowing air under pressure to pass from an air supply hose 73, through an air passageway 74 in the valve casing 35 around the valve 36 at the groove 41 through the air port 43, and into the cylinder 32. The entrance of the air under pressure into the cylinder 32 will move the piston 31 to the left and, due to its operative engagement with the yoke 26; a similar movement will be imparted thereto, thus moving the feed block 25 to the left (Fig. 7), so as to allow the lowermost part 72 to rest upon the reduced portion 27. This movement of the piston and its cooperating parts is effected during the time in which the annular groove 41 is in communication with the air port 43, and during this time the annular groove 42 is positioned in communication with the air port 44, thus allowing the air which is in the cylinder 32, at the left of the piston (Fig. 5), to pass through the air port 44, around the valve 36 at the groove 42, and through an exhaust port 75 (Fig. 2). The valve 36 is held in this position during the engagement of the cam lever 52 therewith, and as soon as the cam surface 63 of the cam lever 52 is free from the cam surface 64 of the valve 36, the valve will be moved into its normal position by the spring 45, thus moving the annular grooves 41 and 42 out of registration with the air ports 43 and 44 respectively.

Upon the upward movement of the punch holder 54 the cam lever 52 will be swung outwardly about its pivot by the engagement of the cam surface 65 thereof, with the cam surface 66 of the slide valve 36 without actuating the slide valve. However, during this upward movement of the punch holder 54 the cam lever 53 will move the slide valve 37 to the left due to the engagement of the actuating cam surface 69 of the cam lever 53 with the actuating cam surface 71 of the valve 37. This movement of the valve 37 will position the annular groove 48 in communication with the air port 43 so as to exhaust the air in the cylinder 32 at the right of the piston 31 through an exhaust port 76 while the piston 31 is moved to the right by the entrance of air under pressure into the cylinder 32 at the left of the piston through an air passageway 77 from the air line 73 through the groove 47 and the air port 44. The piston, due to the air under pressure in the cylinder 32 at the left thereof, will be moved to the right, thus 120

moving with it the yoke 26 and the feed block 25. As the feed block 25 is moved relative to the magazine 23, the lowermost part 72 which rests upon the reduced portion 27 will be moved to the right into a passageway 78 provided between the cover 22 and a guide plate or member 79 due to the abutting engagement of the shoulder 28 with the part. The feed block is again moved to the left as heretofore described, allowing the next part to rest upon the reduced portion 27 and to be moved to the right by the movement of the feed block in that direction so as to advance the first moved part toward the die plates 15 and 16. This operation is continued during the reciprocal movement of the punch holder 54 and the responsive movements of the piston 31 and its cooperating parts due to the actuation of the slide valves 36 and 37. The end parts; that is, the parts in the passageway 78 adjacent the magazine 23 and the die plate 15, are held against movement, other than that imparted to these parts due to the actuation of the feed plate, by retaining pins 80 and 81 which are normally held downwardly by a spring 82. During this reciprocatory movement of the part toward the die plates 15 and 16, the part at the delivery end of the passageway 78 will be moved so that its forward edge will abut a stop member 83 which is held in effective position by a spring 95. This positioning of the part is brought about while the punch holder 54 and the punch 84, which is carried thereby, are in their uppermost positions. The part remains in this position until the punch 84, during its downward movement, (Fig. 7), moves the part into the aperture between the die plates 15 and 16 against the spring pressed plunger 18, thus causing the forward edge of the part to be bent upwardly. During this downward movement of the punch holder 54 and the punch 84 a projection or setting pin 85, which is carried by the punch holder 54, engages with a stop member 83 and moves the stop member downwardly so that the upper edge thereof will be flush with the upper edge of the die plate 16 where it is held by a spring actuated latch 86 which has an engaging portion receivable in a slot 87 of the stop member 83. During the upward movement of the punch holder 54 and the punch 84, the part 72 which has been formed will be moved free from the die plates 15 and 16 by the spring actuated plunger 18 and allowed to pass free of the apparatus down the slide 88. This operation is continued and controlled by the reciprocatory movement of the punch holder 54, which, due to the cam levers 52 and 53, actuate the valve 37, upon the upstroke of the punch holder for actuating the feeding mechanism so as to move a new part adjacent the stop member 83, and actuate the valve 36, upon the downstroke of the punch

84, so as to move another part from the magazine, together with the parts in the passageway 78, forwardly. The yoke 26 is in abutting relation with the latch 86 so as to actuate the latch and release the stop member 83 during the forward movement thereof and before the foremost part has been moved adjacent to the stop member 83. The stop member 83, therefore, positions the part properly relative to the die plates 15 and 16 and is lowered so as to allow the formed part to pass freely from the apparatus before it is again released to position the next part to be formed.

It should be understood that the feeding mechanism, which has been shown in this embodiment applied to a forming apparatus, can be applied to various types of processing apparatus and function efficiently for the purpose intended. It should also be understood that the apparatus may be adapted to feed different forms of articles to processing machines merely by changing the head or the magazine so as to accommodate the different articles.

With this apparatus merely one power connection is needed and that connection is for supplying fluid under pressure through the novel arrangement of passageways for admitting the fluid under pressure alternately to the two sides of the piston and for exhausting the spent fluid alternately through the same passageways. This novel means for admitting and exhausting the fluid consists of the arrangement of the passageways 43 and 44 which communicate with the supply line 73 for alternately admitting the fluid under pressure to the sides of the piston 31 and for alternately allowing the spent fluid to be exhausted therethrough and into the atmosphere through the communicating ports 75 and 76. Under certain conditions it might be desirable to dispose needle valves in the exhaust ports 75 and 76 for the purpose of cushioning the movement of the piston 31. Furthermore, with the novel valve construction the actuated valve allows the fluid under pressure to pass into the cylinder at one side of the piston and at the same time allows the spent fluid to be exhausted from the cylinder at the opposite side of the piston, while the other valve shuts off communication with its adjacent passageways and the fluid supply line so as to bring about an accurate, positive and automatic operation of the apparatus.

Although the invention has been described as a material feeding apparatus for a forming machine, it is to be understood that the material feeding apparatus may be used in cooperation with any other form of processing machine without departing from the spirit and scope of the invention.

What is claimed is:

1. In a material feeding apparatus, a valve, means movable in one direction for actuat-

ing said valve, means responsive to the actuation of said valve for moving articles of manufacture, and means whereby said valve actuating means may be moved in another direction without actuating said valve.

2. In a material feeding apparatus, means for receiving a plurality of articles of manufacture, means adapted to be reciprocated for removing the articles of manufacture singly from said receiving means, valve means, means movable in one direction for actuating said valve means for moving said reciprocating means in one direction, and means movable in the opposite direction for actuating said valve means for moving said reciprocating means in the opposite direction.

3. In a material feeding apparatus, a reciprocating means, a valve, a cam lever carried by said reciprocating member and disposed in operative engagement of said valve whereby said cam lever may actuate said valve during one movement of said reciprocating member, means for receiving articles of manufacture, reciprocating means disposed adjacent said receiving means, and means responsive to the actuation of said valve for moving said reciprocating means in one direction whereby an article of manufacture may be removed from said receiving means.

4. The combination with a processing apparatus having a movable member, of a cam member carried by said movable member, means actuated by said cam member for moving an article of manufacture toward said movable member, a stop member whereby said article of manufacture may be positioned adjacent said movable member, and means for actuating said stop member whereby said article of manufacture may be moved free of said movable member.

5. In a material feeding apparatus, a valve casing having an air port therein, a valve disposed of said casing, means responsive to the actuation of said valve for moving an article of manufacture, and means for actuating said valve whereby a fluid under pressure may pass through said port and actuate said article moving means, said port being arranged whereby said fluid may be exhausted therethrough.

6. In a material feeding apparatus, a valve casing having an air port therein, a valve disposed in said casing, means responsive to the actuation of said valve for moving an article of manufacture, a cam lever having a cam surface adapted to engage with said valve for moving said valve whereby a fluid under pressure may pass through said port and actuate said article moving means when said lever is moved in one direction, and means whereby said lever may be moved in the opposite direction free of said valve whereby said valve may be released.

65 7. In a material feeding apparatus, valve

actuating cam levers adapted to be reciprocated, valves adapted to be actuated by said valve actuating cam levers, an article moving member, means responsive to the actuation of said valves for reciprocating the article moving member, and means whereby said valves may be alternately actuated during the reciprocatory movement of said valve actuating cam levers for actuating said article moving member.

8. In a material feeding apparatus, valve actuating cam levers adapted to be reciprocated, valves adapted to be actuated by said valve actuating cam levers, an article moving member, means responsive to the actuation of said valves for reciprocating said article moving member, means whereby said valves may be alternately actuated during the reciprocatory movement of said valve actuating cam levers for actuating said article moving member, said means comprising a cam surface of one of said levers adapted to engage with a cam surface of one of said valves for actuating said valve when said lever is moved in one direction.

9. In a material feeding apparatus, valve actuating cam levers adapted to be reciprocated, valves adapted to be actuated by said valve actuating cam levers, an article moving member, means responsive to the actuation of said valves for reciprocating said article moving member, means whereby said valves may be alternately actuated during the reciprocatory movement of said valve actuating cam levers for actuating said article moving member, said means comprising a cam surface of one of said levers adapted to engage with a cam surface of one of said valves for actuating said valve when said lever is moved in one direction, and a cam surface of the other of said levers adapted to engage with the cam surface of the other of said valves for actuating the last named valve when said last named lever is moved in the opposite direction.

10. In a material feeding apparatus, valve actuating cam levers adapted to be reciprocated, valves adapted to be actuated by said valve actuating cam levers, an article moving member, means responsive to the actuation of said valves for reciprocating said article moving member, means whereby said valves may be alternately actuated during the reciprocatory movement of said valve actuating cam levers for actuating said article moving member, said means comprising a cam surface of one of said levers adapted to engage with a cam surface of one of said valves for actuating said valve when said lever is moved in one direction, a cam surface of the other of said levers adapted to engage with the cam surface of the other of said valves for actuating the last named valve when the last named lever is moved in the opposite direction, and means whereby said levers may be alternately

moved free of said valves during the reciprocatory movement thereof.

11. In a material feeding apparatus, valve actuating cam levers adapted to be reciprocated, valves adapted to be actuated by said valve actuating cam levers, an article moving member, means responsive to the actuation of said valves for reciprocating said article moving member, means whereby said valves may be alternately actuated during the reciprocatory movement of said valve actuating cam levers for actuating said article moving member, and means whereby said levers may be adjusted relative to said valves for varying the actuation of said valves.

12. In a material feeding apparatus, valve actuating cam levers adapted to be reciprocated, valves adapted to be actuated by said valve actuating cam levers, an article moving member, means responsive to the actuation of said valves for reciprocating the article moving member, means whereby said valves may be alternately actuated during the reciprocatory movement of said valve actuating cam levers for actuating said article moving member, and means for varying the positions of said levers relative to said valves and relative to each other for varying the actuation of said valves.

13. In a material feeding apparatus, a valve casing having fluid ports therin, valves disposed in said casing and adapted to open and close said fluid ports, valve actuating cam levers adapted to be reciprocated, means carried by said valve actuating cam levers for alternately actuating said valves during the reciprocatory movement thereof, whereby said ports may alternately receive a fluid under pressure and alternately exhaust a spent fluid, and means communicating with said fluid ports for moving articles of manufacture.

14. In a material feeding apparatus, a valve casing having fluid ports therein, valves disposed in said casing and adapted to open and close said fluid ports, valve actuating cam levers adapted to be reciprocated, means carried by said valve actuating cam levers for alternately actuating said valves during the reciprocatory movement thereof, whereby said ports may alternately receive a fluid under pressure and alternately exhaust a spent fluid, means communicating with said fluid ports for moving articles of manufacture, said article moving means comprising a cylinder, a piston disposed in said cylinder and adapted to be actuated by the fluid under pressure, and means operatively connected to said piston for moving the articles of manufacture.

15. In a material feeding apparatus, a valve casing having fluid ports therein, valves disposed in said casing and adapted to open and close said fluid ports, valve actuating cam levers adapted to be reciprocated, means car-

ried by said valve actuating cam levers for alternately actuating said valves during the reciprocatory movement thereof, whereby said ports may alternately receive a fluid under pressure and alternately exhaust a spent fluid, means communicating with said fluid ports for moving articles of manufacture, said article moving means comprising a cylinder, a piston disposed in said cylinder and adapted to be actuated by the fluid under pressure, a yoke operatively connected to said piston, and means carried by said yoke for moving articles of manufacture when said yoke is actuated by said piston.

In witness whereof I hereunto subscribe my name this 31st day of January A. D., 1930.
